UNITED STATES PATENT OFFICE

2,263,795

BUILDING CONSTRUCTION

Bruno E. Balduf, Chicago, Ill., assignor to United States Gypsum Company, Chicago, Ill., a corporation of Illinois

Application August 1, 1938. Serial No. 222,389

11 Claims. (Cl. 72—118)

This invention relates to building constructions, and has reference more particularly to building constructions in which building boards are rigidly supported on frame members.

In the construction of wood frame buildings to which gypsum boards and plaster are applied, it has been found that cracks are apt to form in the plaster due to warping or twisting of the frame members. This cracking effect is especially noticeable where the gypsum or other building boards are rigidly nailed to the frame members. Furthermore when plaster boards are attached to frame members in face abutting relation, joist marks are apt to appear on the finished wall adjacent the frame members. It is also customary to rigidly attach plaster boards to the frame members at the corners of the room at the ceiling, and contraction and expansion of the ceiling due to temperature changes produces serious corner cracks in spite of Cornerite or other corner reinforcement.

An object of the invention therefore, is to provide pivotally mounted clips for rigidly attaching plaster boards to frame members so as to eliminate cracking in the plaster.

Another object of the invention is to space the plaster boards a short distance from the frame members so as to eliminate joist marks in the plaster, and to lower the sound transmission through a partition.

A further object of the invention is to provide a floating corner construction so that expansion and contraction of a ceiling will not produce corner cracks; also to improve building constructions and clips in other respects hereinafter specified and claimed.

This application is a continuation in part of application of Bruno E. Balduf "Partition structure," Ser. No. 179,967, filed December 15, 1937.

Reference is to be had to the accompanying drawings forming a part of this specification, in which

Fig. 1 is a perspective sectional elevation of a portion of a building showing the preferred form of my improved full floating construction,

Fig. 2 is a perspective sectional elevation showing a modified form of construction in which only the corners are free floating,

Fig. 3 is a perspective sectional elevation of a vertical corner of a room with floating corners,

Fig. 4 is a perspective sectional elevation of a room adjacent a stairway using floating corners,

Fig. 5 is an elevation of a room adjacent a window,

Fig. 6 is an elevation of a room adjacent a door,

Fig. 7 is a sectional plan view through an exterior corner of a room,

Fig. 8 is a sectional plan view through an interior corner of a room,

Fig. 9 is a perspective view of a corner clip,

Fig. 10 is a perspective view of a pivotally arranged board attaching clip,

Fig. 11 is a plan view of the clip shown in Fig. 10,

Fig. 12 is a sectional plan view of a wooden frame member, board and clip shown in Figs. 10 and 11,

Fig. 13 is sectional plan view through a building frame construction in which the frame has been twisted out of its normal position,

Fig. 14 is a sectional plan view through a building construction utilizing a modified form of clip to space the boards from the building frame,

Fig. 15 is a sectional plan view through a modified form of pivoted clip for attachment to metal frame members, and

Fig. 16 is a perspective view of a clip for connecting the ends of plaster boards.

In the form of my improved building clip shown in Figs. 10-13, inclusive, a body 20 is provided with opposed outstanding flanges 21 and 22 forming oppositely directed channels to receive and support the adjacent edges of plaster boards 23. The boards 23 are preferably provided with a plurality of perforations 24 which serve to improve the bond of a plaster layer 25 which is applied to the exposed faces of the boards. The flanges 22 have outwardly curved ends 26 which insure that the boards 23 can be easily inserted in the clip channels and also insure that a sufficiently thick layer of plaster will be applied to the board faces. An L-shaped

attaching member 27 is pivotally secured to the body 20 by means of a pivot pin 28 so that the member 27 has limited pivotal movement relative to the body 20. It will be noted that the axis of pin 28 extends parallel with the plane of the boards 23. A transversely extending flange 29 on the member 27 is provided with a plurality of apertures 30 to receive nails 31 which are driven into a stud 32 or other building frame in order to support said clip. It will be seen from an inspection of Fig. 12 that the rear face of boards 23 is spaced away from the stud 32 by the thickness of flanges 21 so that stud marks will not form on the exposed face of plaster layer 25. This spacing of the boards from the studs

also greatly lowers the sound transmission of a

10

15

20

wall over a wall in which the boards lie in face abutting position against the studs. As shown in Figs. 11-13 the attaching member 27 may be moved to any position intermediate the full line position and the dot-and-dash position so that as the frame member 32 warps or twists the attaching member 27 provides a yielding connection to prevent cracking of the plaster layer 25. In the form of clip shown in Fig. 14, a special attaching member 27a is provided with an outstanding flange 34 to engage the face of stud 32 and provide a greater distance between the inner board face 35 and the stud, thus more effectively preventing stud marks on the exposed plaster surface. In the form of clip shown in Fig. 15, an attaching member 36 is pivotally secured to a clip body 37 by means of pivot pin 38. An outstanding flange 39 is formed on the member 36 and is adapted to be bent around a steel channel 40 or other metal section for attachment purposes.

It will be seen that the clips described serve to yieldingly attach the boards 23 to the frame members in the field, or main expanse of the wall or ceiling. Another important feature of my invention consists in providing free floating corners in which the boards are disconnected from the frame members at the corners of the room to permit free expansion and contraction and eliminate corner cracks. For this purpose, I provide a corner clip 42 (Fig. 9) presenting channels arranged at right angles to receive the edges of plaster boards at the corner of a room. The body 43 of the clip 42 is provided with a right angle flange 44 along one edge, and finger flanges 45 along the other edge. Between the flanges 45, are L-shaped flanges 46, the entire structure loosely and yieldingly connecting the adjacent edges of building boards meeting at a 90° angle, either interior or exterior. The corner clip 42 is not secured to corner frame members 48 but merely lies in abutting relation thereto. These corner clips are useful for erection purposes to support the boards while they are being put in place. Were it not for this function in aiding in erection, the corner clips 42 could be omitted and the boards left entirely unsecured to the corner stud to make a corner board construction which is entirely free to permit expansion and contraction of walls and ceilings without forming cracks in the plaster at the corners of a room. The corner clips 42 may be used in the interior corners of the room as shown in Fig. 8, or on the exterior corners of the room as shown in Fig. 7. In either case, Cornerite or corner reinforcing is unnecessary to prevent corner cracks.

In the form of modified construction shown in Figs. 2-8, inclusive, the boards 23 are nailed directly to the studs 32 in the field of the walls and ceilings by nails 49, but the nails are entirely omitted within about 14 inches of the corners of the room so as to provide this corner floating of the boards to prevent corner cracks in the plaster. In either the preferred form of full floating construction shown in Fig. 1 or the modified form of construction, the boards extend transversely of the studs and the ends of the boards are connected by clips 50 having outstanding fingers forming opposed channels for the reception of the board ends and edges. As the end joints of the boards are staggered, each clip 50 engages the corners of two boards and the longitudinal edge of a third board to resist deflection of the boards under trowel pressure when the plaster 25 is applied. With the end board joints

meeting in a haphazard manner between the studs, waste of boards due to cutting is reduced to a minimum, being only necessary at the corners of a room where nailing to the studs is preferably omitted according to my disclosure. When boards are applied about the doors or windows as shown in Figs. 5 and 6, the boards are not nailed within a foot or so of the window frame or the door frame as this greatly aids in preventing settlement or other cracks around said doors or windows.

I would state in conclusion that, while the illustrated examples constitute practical embodiments of my invention, I do not wish to limit myself precisely to these details, since manifestly the same may be considerably varied without departing from the spirit of the invention as defined in the appended claims.

Having thus described my invention, I claim as new and desire to secure by Letters Patent:

1. In a building construction, a plurality of spaced frame members for supporting walls or ceilings intersecting at corners, building boards secured to said frame members in the field of said walls or ceilings, said building boards being unattached to said frame members at said corners and for a substantial distance from said corners, means for connecting said boards together at said corners and a layer of plaster on the exposed face of said building boards, said plaster being characterized by freedom from corner cracks.

2. In a building construction, a plurality of spaced frame members for supporting walls or ceilings intersecting at corners, building boards yieldingly secured to said frame members in the field of said walls or ceilings, said boards being unattached to said frame members at said corners and for a substantial distance from said corners, means for connecting said boards together at said corners and a layer of plaster on the exposed face of said building boards.

3. In a building construction, a plurality of spaced frame members for supporting walls or ceilings intersecting at an angle to form corners, building boards yieldingly secured to said frame members in the field of said walls or ceilings, the ends of said boards extending beyond said frame members and having abutting ends of said boards connected one to the other, said boards being unattached to said frame members at said corners and for a substantial distance from said corners, means for securing adjacent ends of said boards together at said corners, and a layer of plaster on the exposed face of said building boards, said plaster being characterized by freedom from corner cracks.

4. In a building construction, a plurality of spaced frame members for supporting walls or ceilings intersecting at corners, building boards secured to said frame members in the field of said walls or ceilings, said boards being unattached to said frame members at said corners and for a substantial distance from said corners, angle clips connecting together the ends of said boards adjacent said corners, and a layer of plaster on the exposed face of said building boards.

5. In a building construction, a plurality of spaced frame members for supporting walls or ceilings intersecting at corners, building boards positioned adjacent said frame members, pivotally mounted clips for yieldingly attaching said boards to said frame members, the pivotal axes of said clips extending substantially parallel to said boards, said boards being unattached to said

frame members at said corners and for a substantial distance from said corners, and a layer of plaster on the exposed face of said building boards.

6. In a building construction, a plurality of spaced frame members for supporting walls or ceilings intersecting at corners, building boards positioned adjacent said frame members, and pivotally mounted clips for yieldingly attaching said boards to said frame members, the pivotal axes of said clips extending substantially parallel to said boards, said boards being unattached to said frame members at the corners of said building construction and for a substantial distance from said corners, and a layer of plaster on the exposed face of said building boards.

7. A building clip comprising a body member, finger flanges formed on said member and forming oppositely extending channels for the reception of the adjacent edges of building boards, and a frame attaching member pivotally secured to said body member, the axis of said pivot extending substantially parallel to said boards.

8. In a building construction, a studding or the like support for panel boards, a building clip secured to said support, said clip comprising a body member having finger flanges forming oppositely extending channels, building boards supported in said channels with their edges adjacent said body member, and securing means extending into at least one of said channels and between said panel board edges and extending laterally from said clip to secure said clip to said support, said securing means having a pivotal connection with said clip to enable sufficient relative movement therebetween to permit limited self alignment of said clip independently of said support.

9. In a building construction, a plurality of spaced frame members for supporting walls or ceilings intersecting at corners, building boards positioned adjacent said frame members, pivot-

ally mounted clips for yieldingly attaching said boards to said frame members, the pivotal axes of said clips extending substantially parallel to said boards, said boards being unattached to said frame members at the corners of said building construction and for a substantial distance from said corners, and a layer of plaster on the exposed face of said building boards.

10. In a building construction, a plurality of spaced frame members for supporting walls or ceilings intersecting at corners, building boards positioned adjacent said frame members, means for connecting said boards together adjacent said corners, clips in the field of said wall or ceiling and engaging with the edge portion of said boards to hold said boards substantially in alignment, means for supporting the respective clips on adjacent frame members, each of said means having a flexible connection with its associated clip to enable relative self-aligning movement of said clips, said clips having fingers which yieldingly engage said boards, said boards being unattached to said frame members at said corners and for a substantial distance from said corners, and a layer of plaster on the exposed face of said building boards, said plaster being characterized by freedom from cracks.

11. In a building construction, a plurality of spaced frame members for supporting walls or ceilings intersecting at corners, building boards positioned adjacent said frame members, clips in the field of said wall or ceiling and engaging with the edge portion of said boards to hold said boards substantially in alignment, means for supporting the respective clips on adjacent frame members, each of said means having a flexible connection with its associated clip to enable relative self-aligning movement of said clips, angle clips connecting together the ends of said boards adjacent said corners, said boards being unattached to said frame members at said corners and for a substantial distance from said corners, and a layer of plaster on the exposed face of said building boards, said plaster being characterized by freedom from cracks.

BRUNO E. BALDUF.
